UNITED STATES PATENT OFFICE.

HARRY L. VAUGHAN, OF CHICAGO, ILLINOIS, ASSIGNOR TO VAUGHAN NOVELTY MFG. CO., OF CHICAGO, ILLINOIS, A CORPORATION OF ILLINOIS.

CAN OPENER.

Application filed August 11, 1928. Serial No. 298,931.

This invention relates to improvements in can openers, and more especially to the combination with can openers of an approved and extensively used style, of added features calculated to increase its usefulness.

Accordingly, one of the objects of the invention is to provide a guard to protect the hand in which the opener is held, and more especially the thumb thereof, against cutting by the sharp jagged edges of the tin, in opening a can. Another object is to provide an additional tool in the form of an opener for friction-top containers having a shouldered or flanged top or cover intended to be removed by inserting a blunt edge under the marginal flange of the cover and prying upwardly at several points about the edge.

In the drawings, a preferred embodiment of the improved can opener is shown in which

Figure 1 is a perspective view of the opener showing the guard and friction-top opener applied thereto, the latter being in open position.

Figure 2 is a perspective view of a modified arrangement wherein the guard and friction-top opener are combined in a single piece, and

Figure 3 is a perspective view of the end of the opener, showing the friction-top opener as an integral part thereof.

The type of can opener to which the improvements are particularly applicable is one having a short pointed blade or knife 1 fixed to a handle 2, having a projection 3 spaced from the sharpened edge of the blade. This style of can opener is manipulated by initially forcing the point of the blade through the can top near its edge and thence creeping around the edge with short cutting strokes, using the forward edge of the projection 3 as a fulcrum.

The can opener herein disclosed is preferably an all-metal style, in which the handle 2 and projection 3 are made in one piece, namely, of a single flat bar of metal shaped and bent to provide an open handle square at its outer end and tapering at its forward end where the two portions of the metal bar come together to form a narrow neck or shank portion 4 between the handle and projection 3. The projection 3 has the form of a loop with a square forward end. The blade 1 is secured at the shank 4, having a

portion inserted between the metal bars and fixed by rivets 5, 5 passing through the shank portion on either side of the junction (at 6) of the ends of the metal strip forming the body or frame of the opener. The 60 pointed blade extends downwardly and thence forwardly beyond the projection 3, with its cutting edge 1^a parallel with and spaced from the under side of said projection, the forward edge of the latter being 65 notched at 3^a to grip the edge of the can to prevent the opener from slipping. Integral with the blade 1 and projecting from the opposite side of the shank portion 4 is a hook-like blade 7, facing forwardly and coacting 70 with the upper edge of the projection 3 to form an opener for bottles having crown seals or caps.

Just behind the blade and pivotally mounted in a narrow space opening into the 75 wider space forming the handle is a corkscrew 8, its inner end being bent around a rivet 9 acting as a fulcrum. The corkscrew normally lies within the space in the handle and is swung outwardly at right angles to the 80 handle for use.

Fixed to the shank portion 4, near its junction with the handle, is the thumb guard 10. This member is a metal stamping consisting of a flat bottom wall 10^a tapering toward its 85 front end and having an upturned flange 10^b along its outer edge, the forward portion of the flange being approximately $\frac{3}{8}$ of an inch in height and rounded, falling off to $\frac{1}{8}$ of an inch at the sides. Along the inner edge of 90 the guard is an ear 11, bent at right angles to the bottom wall, in flatwise contact with the side of the shank portion 4. Through this ear extends the end of the rivet 9 which also serves as the bearing for the corkscrew. The 95 ear is of such a height that when it is fastened in place with its top edge flush with the edge of the shank, the bottom wall of the guard is offset at least $\frac{1}{8}$ of an inch below the bottom edge of the shank and substantially in alignment with the cutting edge of the blade 1.

Assuming that the opener is held in the right hand, the guard is mounted on the left side thereof so that when the handle is grasped in the fingers the tip of the thumb of the right hand fits into the pocket formed between the flanged edges of the guard and the side of the shank 4, thus being protected from contact with jagged edges of the can which pass beneath the guard as the cutting pro- 110

ceeds. In this manner the thumb and fingers which otherwise are liable to be cut, should the opener slip, are protected.

The friction-top removing tool is preferably mounted at the rear or free end of the handle and consisting of a short, stout blade 12, tapering to a blunt edge of about $\frac{1}{4}$ of an inch in width, and turned upwardly with a slight reversed bend at 12^a just inwardly 10 therefrom to afford the necessary leverage when prying off the cover.

The blade is approximately 1 inch in length, and at its rear end is a V-shaped bend 12^b, there being laterally projecting ears 13, 15 at the extreme ends of the blade which has pivotal connection with the handle inwardly from its rear end in holes 14 punched in the sides of the handle.

In operating position the blade 12 projects 20 from the rear end of the handle with the V-shaped portion 12^b engaging the rear edge of the handle. When not in use the blade is closed by turning it over and forcing it into the space in the handle overlying the corking 25 screw, the sides of the handle being slightly sprung to hold the blade in place, as shown in dotted lines in Figure 1.

As a practical modification of the features hereinbefore disclosed and as a possible expedient for combining the guard and friction-top removing tool, Figure 2 shows the bottom wall of the guard extended rearwardly and outwardly in a tapered projection 15, having an end portion similar in all respects to that 35 of the blade 12 pivotally mounted at the rear end of the handle.

Figure 3 shows a further modification in which the friction-top opener blade 16 is formed integral with the forward projection 3 of the opener. 40

Having set forth the preferred arrangement of a can opener embodying the features of my invention,

I claim:

1. A can opener comprising a handle, a cutting blade at the forward end of said handle, and a guard fixed to said handle rearwardly of said blade and consisting of a plate projecting laterally from the handle and provided with a forward marginal guard flange. 45 50

2. A can opener comprising a handle, a cutting blade at the forward end of said handle, and a guard fixed to said handle rearwardly of said blade and consisting of a metal plate extending laterally from said handle and tapered toward its forward end, the edges of said plate being bent upwardly to form a guard flange at the front and sides of said plate. 55

3. A can opener comprising a handle, a cutting blade at the forward end of said handle, and a guard fixed to said handle rearwardly of said blade and consisting of a metal plate extending laterally from said handle and tapered toward its forward end, the edges of said plate being bent upwardly to form a relatively high guard flange at the forward edge of the plate tapering to a lower flange 60 65 along the outer side edge thereof.

Signed at Chicago, Ill., this 6th day of 70 August, 1928.

HARRY L. VAUGHAN.
